[57] CLAIM

The ornamental design for a passenger tunnel for a conveyance loader, substantially as shown and described.

DESCRIPTION

FIG. 1 is a side elevation view showing one side of a passenger tunnel for a conveyance loader embodying my new design;

FIG. 2 is a view similar to FIG. 1 and showing the other side thereof;

FIG. 3 is a top plan view thereof;

FIG. 4 is a bottom plan view thereof;

FIG. 5 is an end elevation view showing one end thereof; and

FIG. 6 is a view similar to FIG. 5 and showing the other end thereof.

The structure shown in broken lines in FIGS. 1, 2 and 4-6 is for controlling movement of components of the passenger tunnel for a conveyance loader, and is shown for illustration purposes only.
